(57) CLAIM

The ornamental design for a stethoscope watch, as shown and described.

DESCRIPTION

FIG. 1 is an environmental perspective view of a stethoscope watch showing my new design;

FIG. 2 is an environmental top plan view thereof;

FIG. 3 is a bottom plan view thereof;

FIG. 4 is a front elevational view thereof;

FIG. 5 is a rear elevational view thereof; and,

FIG. 6 is a right elevational view with the left side being a mirror image thereof.

The broken line showing of the human hand in FIGS. 1 and 2 is for illustrative purposes only and forms no part of the claimed design. The broken line showing of the heart-shaped second indicator in FIG. 2 is for illustrative purposes only, merely disclosing the type of second hand which may be used, and forms no part of the claimed design. The broken line showing of the minute and hour hands and the numerals in FIGS. 1 and 2 is for illustrative purposes only, merely disclosing the types of attachments and indicia which may be used, and forms no part of the claimed design.
